CLAIM

The ornamental design for a shutter for a bird feeder, as shown and described.

DESCRIPTION

FIG. 1 is a top right perspective view of a shutter for a bird feeder of the present invention.

FIG. 2 a top left perspective view of the shutter for a bird feeder of FIG. 1.

FIG. 3 is a right side elevational view of the shutter for a bird feeder of FIG. 1.

FIG. 4 is a top, right perspective view of the shutter for a bird feeder of FIG. 1, shown in an open and expanded state.

FIG. 5 is a front elevational view of the shutter for a bird feeder of FIG. 1.

FIG. 6 is a rear elevational view of the shutter for a bird feeder of FIG. 1.

FIG. 7 is a bottom plan view of the shutter for a bird feeder of FIG. 1; and,

FIG. 8 is a top plan view of the shutter for a bird feeder of FIG. 1.
